UNITED STATES PATENT OFFICE.

ARTHUR A. WEISBERGER, OF CHICAGO, ILLINOIS.

AUTOMATIC GAS-STOVE LIGHTER.

Application filed October 31, 1927. Serial No. 230,011.

This invention relates to automatic igniting devices and pertains particularly to an automatic ignitor designed for use in connection with gas stove burners.

5 The primary objects of the present invention is to provide, in a manner as hereinafter set forth, a device designed to ignite a gas burner or similar gas fixture, automatically and simultaneously with the turning on of the control valve.

Another object of the invention is to provide, in a manner as hereinafter set forth, an automatic ignitor which, when the gas fixture in association with which it is used 15 is in use, will act as a pilot to re-light the fixture in the event that the same is accidentally put out.

The invention has for another object the provision of an automatic lighting device 20 for use in association with gas fixtures, wherein a gas jet is ignited independently of the fixture and acts to light the fixture when the control valve thereof is turned on, the lighting jet continuing to burn while 25 the fixture is in use and acting in the event of accidental extinguishment of the fixture, to re-light the same, the jet being so located and protected that the possibility of it being extinguished, is very slight.

30 A further object of the invention is to provide an automatic lighting means for gas fixtures of the character described, which will be of simple but strong and durable construction requiring little or no attention, and having a minimum of moving parts to get out of order.

Numerous other objects and advantages of the present invention will become apparent as the description of the same proceeds and 40 the invention will be best understood from a consideration of the following detailed description taken in connection with the accompanying drawings forming a part of this specification, with the understanding, 45 however, that the invention is not confined to any strict conformity with the showing of the drawing but may be changed or modified so long as such changes or modifications mark no material departure from the salient 50 features of the invention as expressed in the appended claims.

In the drawings:

Figure 1 is a top plan view of the invention described.

55 Figure 2 is a side elevational view of the structure embodying the present invention.

Figure 3 is a section taken substantially upon the line 3-3 of Figure 1.

Figure 4 is a plan view of the main portion of the invention showing the same in 60 one position assumed in the first part of the operative movement of the device.

Figure 5 is a transverse section taken substantially upon the line 5-5 of Figure 1.

Figure 6 is a section taken substantially 65 upon the line 6-6 of Figure 1.

Referring now to the drawings in detail wherein like numerals of reference indicate corresponding parts throughout the several views, the numeral 1 indicates a portion of 70 a gas manifold from which one or more gas fixtures of the type indicated by the numeral 2 are fed. The fixture 2 here shown is conventionally illustrated and symbolizes the usual gas range burner which has the feed 75 pipe 3 leading thereto the outer end of which pipe is bell shaped as indicated at 4, in the usual manner. A valve body indicated generally by the numeral 5 is tapped in the manifold body 1 having the coupling 80 6 leading therefrom and the handle 7 controlling the usual plug body 8, the lower end of which projects beyond the valve body 5 as indicated at 9, which end or stem 9 is surrounded by the spring 10 which normally 85 acts to draw the plug 8 into the valve body and thus maintain the same leak-proof. For use in connection with the structure embodying the present invention, the stem 9 has secured thereto the arm 11 which projects rearwardly at an angle with respect to the valve control handle 7. The office of 90 this arm will be described more fully herein-after.

Connected to the valve 5 by means of the 95 coupling 6 is a gas supply line 12 which has the two branches 13 and 14, the branch 13 constituting the pilot supply pipe while the branch 14 extends into and terminates in the burner feed pipe bell 4 as clearly shown 100 in Figure 1. The pilot light supply pipe 13, as shown in Figure 1 branches laterally intermediate its ends and has the free end portion 15 thereof arranged in a plane above the pipe 14 and substantially parallel 105 therewith terminating substantially midway between the burner 2 and the control valve 5, in the pilot tip 16.

Resting upon and extending longitudinally of the burner feed pipe 3 is a supporting block of generally elongated rectangular contour, indicated generally by numeral 17.

This block is provided at each end with the laterally projecting ears 18 each of which is provided with the depending portion 19 which extends downwardly on opposite sides 5 of the pipe 3 as is clearly shown in Figures 3 and 5. Each of these depending portions 19 of the ears 18 has the longitudinally extending bore 20 formed in the lower end to receive the shanks of the screws 21 which 10 pass through the clamp plates 22 and extends across the underside of the pipe 3 as shown.

At the rear of the block 17 is formed the laterally extending apertured bearing 23 15 through which the straight portion 15 of the pilot pipe 13 extends, this pipe being clamped in position in the bearing 23 by the binding screw 24. The upper portion of the block 17 is formed to provide the 20 tubular housing 25 the rear portion of which is internally threaded as at 26 to receive the tension nut 27. The forward portion of the housing body 25 snugly receives a pyrophoric pencil 28 against the rear end of 25 which the tension nut 27 forces the spring 29 which is housed in the rear threaded portion of the housing, the forward end bearing 30 against the rear end of the pencil while the rear end thereof is pressed upon by the tension nut 27 as clearly shown in Figure 6.

Upon the forward end of the body 17 there is mounted in alignment with the housing 27, the ratchet wheel or striker 30 which as shown rotates about the vertical axis of 35 the pin 31. This ratchet 30 bears against the forward end of the pencil 28 which is in alignment transversely of the structure with the pilot tip 16 so that sparks struck from the pencil will pass the end of the pilot tip 40 and ignite gas issuing therefrom.

Surrounding the upper end of the pivot pin 31 is a sleeve 32 which has extending therefrom an integral arm 33, the sleeve at the opposite side being provided with a longitudinally extending rib 34 for the purpose 45 hereinafter to be pointed out. The sleeve 32 and the ratchet 30 are mounted to turn together in a clockwise direction only about the pin 31.

Pivotedly attached as at 35 to the free end 50 of the arm 33 is a dog 36 having the extended portion 37 to the outer end of which is pivotedly attached as at 38 one end of the pull link 39, the other end of this link extending 55 to a point adjacent the valve 5 where it is pivotedly attached as at 40 to the arm 11 which is mounted to rotate with the valve plug 8.

Overlying the pilot tip or nozzle 16 and 60 the ratchet wheel and sleeves 30 and 32 is a cover plate 41 which is primarily intended to protect the mechanism from any substance which may be spilled over the gas burner 2.

A portion of the edge portion of the cover 65 plate 31 is provided with a depending flange

42 to which is secured one end of the spring 43, the free end of this spring extending inwardly and having a groove 44 formed thereacross in which the rib 34 of the sleeve 32 normally engages, preventing the sleeve 70 from turning until sufficient power is applied thereto to force the rib to slip out of the groove 44 in the spring.

The cover plate 41 has the pivot pin 31 passed therethrough and is thus held in position by this pin and in addition a securing screw 45 is passed through the plate at one side and into the fork 46 formed from the side of the housing 25.

From the foregoing description it will be 80 readily seen that when the gas valve handle 7 is turned the supply line will be half opened before the dog 36 swings to the position shown in Figure 4 where it engages the ratchet 30. Further turning of the valve 85 handle 7 will swing the dog through the medium of the connecting links 39, and due to its engagement with the ratchet 30 will cause the arm 33 and the ratchet to turn also, the rib 34 breaking away from the spring 43 as 90 will be readily understood thus causing the teeth of the ratchet wheel 30 to scrape across the pencil 28 and throw sparks across the point of the pilot tip 16 to ignite the gas issuing therefrom. The jet of flame which 95 will be projected from the tip 16 will extend to the burner 2 and thus ignite the gas flowing therefrom and, as will be readily understood, if the gas burning at the burner 2 is accidentally extinguished the pilot will 100 continue to burn and will immediately relight the burner. The closing of the valve 5 will return the arm 33 and dog 36 to original position as shown in Figure 1 ready for further use.

Having thus described my invention what I claim is:

1. In combination, a gas burning element, a valve for controlling the supply of gas to the element, a pyrophoric pencil arranged adjacent the element, a movably mounted striker associated with the pencil, a link connected to the valve, a pivotally mounted arm, and a member pivoted between its ends to the arm and having one end arranged for movement into and out of engagement with the striker and the other end pivoted to the link.

2. In combination, a gas burning element, a valve for controlling the supply of gas to the element, a pyrophoric pencil arranged adjacent the element, a movably mounted striker associated with the pencil, a link connected to the valve, a pivotally mounted arm, a spring engaging the arm, and a member pivoted between its ends to the arm and having one end arranged for movement into and out of engagement with the striker and the other end pivoted to the link.

3. In combination, a gas burner, a valve

- for controlling the supply of gas to the burner, a pyrophoric pencil arranged adjacent the burner, a movably mounted striker associated with the pencil, a member for 5 operating the striker, means for supporting said member for movement from a normally inoperative position into engagement with the striker and for movement in a direction to operate the striker after engagement therewith, and means connecting said member to the valve to permit it to be moved into engagement with the striker and then 10 moved in striker operating direction by and during the opening of the valve and to permit it to be returned to its normally inoperative position by and during the closing of the valve. 15
5. In combination, a gas burner, a valve for controlling the supply of gas to the burner, a pyrophoric pencil arranged adjacent the burner, a movably mounted striker associated with the pencil, a member for 20 operating the striker, means for supporting said member for movement into operative and inoperative position and for movement when in operative position in a direction to operate the striker, and means connecting 25 said member to the valve to permit it to be moved into operative position and then moved in striker operating direction by and during the operation of the valve and to permit it to be returned to its inoperative position by and during the closing of the valve. 30
- 35
4. In combination, a gas burner, a valve for controlling the supply of gas to the burner, a pyrophoric pencil arranged adjacent the burner, a movably mounted striker associated with the pencil, a member for 40 operating the striker, means for supporting said member for movement from a normally inoperative position into engagement with the striker and for movement in a direction to operate the striker after engagement 45
- 50

In testimony whereof I affix my signature.

ARTHUR A. WEISBERGER.
